UNITED STATES PATENT OFFICE.

CHARLES TELLIER, OF PARIS, FRANCE.

MEANS AND APPARATUS FOR UTILIZING WASTE HEAT FOR PRODUCING MOTIVE POWER.

SPECIFICATION forming part of Letters Patent No. 439,259, dated October 28, 1890.

Application filed August 14, 1888, Serial No. 282,720. (No model.) Patented in Belgium January 28, 1888, No. 80,431; in France February 6, 1888, No. 188,572, and in England March 26, 1888, No. 4,637.

To all whom it may concern:

Be it known that I, CHARLES TELLIER, a citizen of the Republic of France, residing at Paris, France, have invented certain new and useful Improvements in the Means and Apparatus for Utilizing Waste Heat for Producing Motive Power, (for which I have obtained Letters Patent in Great Britain, No. 4,637, dated March 26, 1888; in France, No. 188,572, dated February 6, 1888, and in Belgium, No. 80,431, dated January 28, 1888,) of which the following is a specification.

In my application, Serial No. 226,245, filed February 2, 1887, I described an apparatus for utilizing solar or atmospheric heat. The apparatus which I am about to describe has for its object to produce motive power by utilizing the exhaust-steam from steam-engines.

This apparatus is represented in elevation, partly in section, in Figures 1, 1^a, and 1^b in the accompanying drawings.

A is a receiver, into which enters through a tube *a* the exhaust-steam from a condensing or a free-exhaust steam-engine. This receiver is made of five or six times the capacity of the motor-cylinder, as it must be large enough to allow the exhaust to take place without meeting with abnormal resistance, which would weigh uselessly on the motor-piston and diminish its useful effect. The receiver A is directly connected to a chamber or condenser B, which contains a number of tubes opening at one end into the receiver A and at the other end into a collecting-chamber *b*. The exhaust-steam can thus pass freely through the said tubes into the chamber *b*. The condenser B is filled with an aqueous solution of ammonia up to the line *b' b'*. In passing through the tubes of the condenser B the steam in condensing heats the ammoniacal solution, while the water of condensation will run off through the tube *c c'*, whence it can be conducted back by a feed-pump to the boiler of the works. In heating the ammoniacal solution contained in the condenser B the steam will have produced ammoniacal gas, which, disengaged from solution, will be stored in the upper part of the condenser B and in the vapor-

chamber C placed above it. The ammoniacal vapors thus disengaged carry along with them a certain quantity of this solution, which it is important to eliminate. For this purpose I place over the condenser B a vapor-chamber C, communicating with the condenser B by means of tubes *d* for the passage of the ammoniacal vapors, and by means of other tubes *d'* and *d''* for the return of the liquid portion to the bottom of the condenser B. Further, I interpose at the joint *e e* a sheet of very fine wire-gauze, which bursts the scum bubbles drawn along and allow the ammoniacal gas to escape in a pure condition through the tube E, while the liquid runs through the tube *s* into the tube *e' e'*.

Another arrangement consists in placing above the condenser C a steam-chest E', containing a sort of funnel of wire-gauze *e''' e'''*, allowing of the separation of the gas from the scum. The vapors thus produced is of sufficient pressure to be sent into the motor-cylinder. As, however, it has been produced at a temperature of from 50° to 60° centigrade, it can be superheated to 150° or more. For this purpose I cause it to pass through the tubes of a superheater F, around which I cause steam from the boiler of the works to circulate. The steam enters the interchanger F through the tube *f*, and the water of condensation therefrom passes off through the tube *f*, whence it passes to the boiler either directly, if under equal pressure, or by means of a special pump.

The ammoniacal vapor passes out from the vapor-chamber C through the tube *g g* to the base G of the superheater F, rises through its tubes, becomes superheated, and is conducted into the chamber G', placed above the superheater. Thence through a tube *g''* it passes to a motor H, of any suitable known construction, which it actuates, thus producing the required motive power. A tube *g'''* at the base G of the superheater F allows of conducting back into the return-pipe *e' e'* any liquid which might be drawn into the superheater. A tube *g'''' g''''* conducts the ammoniacal vapor which has been employed in the motor-cylinder into an absorption-chamber I, which is made in two parts, one of which is a vapor-

chamber J for receiving the vapors coming from the cylinder H. The other part K more especially serves for effecting the absorption of the said vapors. For this purpose I constantly introduce into the absorbing-chamber K a current of weak ammoniacal solution drawn from the lower part of the condenser B through a tube k. As this solution is hot and it is necessary for it to arrive in as cold a state as possible in the absorbing-chamber K, I first cause it to pass through the interchangers M and N, which will be hereinafter described, and then through the regulating-chamber o, which brings it in a cool state through the tube l into the base of the absorbing-chamber K. In this chamber K the level of the liquid is maintained up to the line l' l' by means of a float L.

The ammoniacal vapors contained in the chamber J pass into contact with the cold solution of the chamber K by means of holes P P P. These holes through tubes p p p p, leading to horizontal tubes p' p' p' p', which are perforated, allow the ammoniacal gas to become dissolved in the cold solution contained in the chamber K; but in order to remove the heat produced by the condensation of the ammoniacal vapors and by their combination I arrange inside the absorbing-chamber K a large number of tubes arranged in clusters or sets, as shown in the caps Q Q' Q'', which allow cold water arriving through a tube q to travel over the clusters of tubes, which water then leaves by the tube q'', having taken up all the caloric. The ammoniacal solution, being thus re-formed, is sent back by means of the pump R into the condenser B to render the operation continuous. As the solution is cold while there is a temperature in the condenser of from 50° to 60°, it is advisable to heat the solution. Now a hot solution is constantly leaving the condenser and passing into the absorbing-chamber K and is required to enter in a cold state. It is advisable therefore to effect an exchange of the heat. For this purpose I conduct the hot solution leaving the condenser through the tube k k k k to the upper part m of the interchanger M. It descends through the tubes of the interchanger to the base m' thereof. Thence it leaves through a tube m''. On the other hand, the cold liquid coming from the absorber K through the tube t is sent by the pump R through the tube x into the lower part of the interchanger M, in which it rises to the top at x'. In rising it becomes heated by contact with the hot liquid coming from the condenser B, so that it leaves in a heated state through the tube e' e' e' e', and is returned to the lower part of the condenser B, while the weak hot solution coming from the condenser B through the tube k enters at m in a hot condition. As its temperature is not yet low enough to allow of its being sent direct into the absorber K, I cause

it to enter the upper part n of a second interchanger N by means of a tube m'' m''. This interchanger is provided with tubes around which circulates a current of cold water, entering at v and leaving at v'. The ammoniacal solution enters the base n'' in a cold condition, whence it is conducted to the absorber K. As the liquid to be cooled enters the interchangers at the top, it is important, in order that the surfaces shall act efficiently, to keep the interchanger-tubes full of liquid. For this purpose I employ an overflow-chamber O, serving to maintain the level of the liquid in the interchangers at the proper height.

From this description it will be understood that the absorber K receives weak liquid at a very low temperature, while the condenser B receives the hot and strong ammoniacal solution. Above the chamber o, in which the float L is placed, serving to maintain the level in the absorber K, is a tube w w, surmounted by a short tube S and a tube s. The tube w w serves to establish the equilibrium between the float L and the absorber K. The tube s leads either to an air-pump and a purifier of suitable construction (not shown in the drawings) or to a blow-off. This arrangement serves to extract the air which may have entered the apparatus and to insure its proper working. The purifier, which may be worked with plain or acidulated water, is for the purpose of collecting the ammoniacal vapors.

The air which may be drawn into the condenser B by the steam is removed by means of a second air-pump communicating with the tube z'.

Another interchanger is shown detached at Z. It is placed there with the object of showing that the vapors passing out of the motor H can be caused to pass through its tubes, and that on the other hand by causing the ammoniacal vapors going to the superheater F to pass around its tubes a portion of the sensible caloric brought by the ammoniacal vapors coming from the motor H can thus be recovered for superheating the said vapors.

Having now particularly described and ascertained the nature of my said invention, and in what manner the same is to be performed, I declare that what I claim is—

In apparatus for producing motive power through the medium of an aqueous solution of ammonia, the combination of the vaporizing-condenser B, provided with the separator hereinbefore described, the superheater F, the absorbing-condenser K, and the temperature-exchangers M and N with a motor H.

CHARLES TELLIER.
